UNITED STATES PATENT OFFICE

2,647,420

RATCHET-TYPE DRILL

Jay W. Stallings, Harrisburg, N. C., assignor of
four-fifths to Jay B. Linker, Milwaukee, Wis.

Application January 2, 1952, Serial No. 264,506

2 Claims. (Cl. 77—44)

1

This invention relates to improvements in drills and more particularly to ratchet type drills for use particularly where the drill press cannot be used due to lack of space or for other reasons. The drill is adapted for use principally as a hand operated drill, as well as for use in lathes, etc.

A further object is to provide a ratchet type drill adapted for use principally in close quarters, that is compact in assembly, positive and efficient in operation and that is free from play, lost motion and wobble when in use.

This and any and all other and more specific objects hereinafter appearing are attained by, and the invention finds preferable embodiment in, the mechanism hereinafter particularly described in this specification and illustrated in the accompanying drawings, wherein:

Fig. 1 is a view in elevational perspective and partly in axial section of a ratchet type drill in accordance with the invention.

Fig. 2 is a view similar to Fig. 1 but rotated to a position at right angles to that figure.

Figs. 3, 4 and 5 are horizontal cross-sectional views taken substantially along the lines 3—3, 4—4, and 5—5 of Fig. 2, respectively.

Fig. 6 is a view in perspective of a drive collar employed.

Fig. 7 is a view in perspective of a type of drill chuck employed.

Fig. 8 is a view of a slightly modified form of drill chuck, mainly in axial section, that may be employed.

Fig. 9 is a horizontal cross-sectional view through Fig. 8 on the line 9—9.

Fig. 10 is an axial sectional view of a further modified form of drill chuck and jack screw, a drill being shown in the chuck.

Fig. 11 is a view similar to Fig. 10 but rotated to a position at right angles thereto.

Fig. 12 is a top plan view of Fig. 10, and

Figs. 13 and 14 are horizontal cross-sectional views taken substantially along the lines 13—13 and 14—14 of Fig. 11.

Like reference characters denote corresponding parts throughout the several views.

Referring now to Figs. 1 to 9 inclusive the reference numeral 1 denotes a tapered drill chuck having a tapered bore 2 and a hexagonal head 3, the head having a hole 4 at right angles to the axis of the chuck to receive a conventional drift (not shown) for removal of the drill 5 from the chuck, the head formed interiorly with a flat sided recess 6 registering with the hole 4 to receive the flat end of certain taper-shank drills, this recess serving to pre-

vent turning of the drill chuck independently of the drill.

The chuck head 3 is snugly and removably received in a socket 7 in one end of the drive collar 8, said collar being hexagonal in contour throughout a portion of its extent, the head 3 of said chuck formed with a perforation 9 axially thereof and registering with the hole 4, said perforation V-shaped from a point 10, spaced a short distance from the hole 4, to the adjacent face of said head, said perforation 9 receiving the center 11 of the head portion 12 of the drive screw 13 received in the square hole 7' in drive collar 8, said head 12 received directly upon said chuck head 3.

The head 12 of the drive screw 13 is formed in short spaced relation to its free terminal with a socket 14 for the spring ball retainer assembly, the ball portion thereof riding releasably in the

10 annular V-shaped recess 16 formed in the inner wall of said collar 8 in spaced relation to the socket 7 at such point that with the center 4 of the drive screw 13 received in the V-shaped portion of perforation 9 said spring ball retainer

15 will be disposed in the recess 16.

The head 12 of the drive screw 13 extends beyond the collar 8 and is formed with a socket 17 for the spring ball retainer assembly 18, the ball portion of which rides in the V-

20 shaped annular recess 19 in the ratchet wheel 20 of the ratchet 21 having the pawl 22 and reversing lever 23, said ratchet having a handle 24 for use by the operator. The feed screw 13 includes a stem 25, square threaded, and receiving the knurled feed nut 26 having pin holes

25 27 and a center 28. In operation the invention

may be conveniently used in lathe work for drilling jobs by using the hexagon headed drill sleeve 1 for holding either taper or straight flat side-shank drills and placing the center in the

30 hexagon head on the lathe stock center, after having placed the ratchet 21 over the hexagon head and having removed parts 12 and 26, and chucking the work to be drilled in the lathe chuck. The ratchet and handle 21, 24 are used

35 to prevent the drill from turning while the lathe work is turned and the tail stock screwed into the work, this being a decided improvement over conventional tools for this type of lathe drilling work. However if it is desired a more simple

40 application of the invention can be used in lathe drilling work, in which event the entire assembly may be used as shown in Figs. 1 and 2, the lathe tail stock center having been removed and the 45 hand nut center 28 placed in the lathe stock cen-

ter hole; or a special centered female center can be used to receive the hand nut center 28 and by holding the ratchet handle in the left hand and gripping the hand nut the drill will be forced into the revolving work.

For other close quarter drilling jobs the invention is a decided improvement over the conventional hand ratchet drills in that it is more compact, more rigid, shorter, and may be used with any conventional ratchet with square holes to fit the head 12. In other drilling operations the invention may be set up and used with the so-called "Old Man," with an angle bar for turning the jack screw to force the drill into the work, and metal or wood spacers may be used to properly space the assembly between the jack support and the centered hand nut 26. With the assembly in proper order the drilling is accomplished by turning the drill sleeve and drill by means of the hand ratchet while keeping the feed nut tightened by hand. It will be noted that the assembly is so arranged as to semi-automatically feed the drill into the work through friction on the hand nut which tends to lengthen out or feed in the assembly as the ratchet is rotated clockwise, threads in the nut being counter to the direction of ratchet rotation.

In Figs. 8 and 9 a slightly modified form of drill chuck 29 is shown having a straight shank with hexagonal head 30; the shank formed with a straight bore 31 which extends into the head and there is reduced to form the contracted portion 32, the bore 31 being formed with one flat side 33, the bore 31 receiving straight flatside drills with the shank received in the contracted bore 32, the entrance to the bore 32 being round to receive a drift to effect removal of the drill when desired, the chuck shank 29 having threaded wall perforations 34, 35 each to receive a headless screw 36 for engagement with the drill to retain same positively in the chuck.

In Figs. 10 through 14 a ratchet operated drill is provided for use in connection with the ratchet mechanism shown in the preceding figures. A drive collar having a cylindrical body portion 37 having drift hole 37' and closed at one end and there having a square drive head 38 with center 38' is received in the ratchet 21 and secured by spring ball 39 is provided, the body having its bore

formed with left hand box-type threads 40 longitudinally of the driver, said threads meshing with the threads of the chuck 41 to permit adjustment of said members. Four keyways 42 are formed in the chuck 41 for the key 43 operative by the handle 44 fulcrumed to the drive member 37, a spring 45 secured to said member yieldingly retaining said key in locking engagement with said chuck to cause cooperation of said members to rotate the drill 46. Conventional operation of the ratchet will cause rotation of the drill intermittently.

It will be obvious to those skilled in the art that various changes may be made in my device without departing from the spirit of the invention and therefore I do not limit myself to what is shown in the drawings and described in the specification, but only as indicated by the appended claims.

What is claimed is:

1. In a ratchet-type drill, a drive collar having a socket portion and an annular V-recess in spaced relation thereto; a drill chuck received in said socket, a drive screw received in said drive collar and formed with spaced sockets, a ratchet having an annular V-recessed, spring ball retainer assembly connecting the socket portions of said drive screw and the V-recesses of said drive collar and said ratchet, said drive screw having a center received in said drill chuck, and a feed nut carried by said drive screw.

2. In a ratchet-type drill, a threaded cylindrical drive collar closed at one end, a threaded drill chuck received in said drive collar and having a key-way, a key carried by said drive collar yieldingly disposed in said key-way, a drive head at one end of said drive collar and having a socket portion, a ratchet about said drive head formed with an annular V-recess, and a spring ball retainer assembly connecting said V-recess and the socket portion of said drive collar.

JAY W. STALLINGS.
